UNITED STATES PATENT OFFICE

THOMAS G. HAWKES, OF CORNING, NEW YORK.

DESIGN FOR THE ORNAMENTATION OF GLASS, &c.

SPECIFICATION forming part of Design No. 17,837, dated October 25, 1887.

Application filed August 31, 1887. Serial No. 248,421. Term of patent 3½ years.

To all whom it may concern:

Be it known that I, THOMAS G. HAWKES, a citizen of the United States, residing at Corning, in the county of Steuben and State of New York, have invented and produced a new and original Design for the Ornamentation of Glass and other Ware, of which the following is a specification, reference being had to the accompanying photograph, forming part thereof.

I show my design applied as an ornament to a glass dish. It consists of a star having a central rosette, 1, surrounded by a circle, 2, from which extend tangential lines 3 in different directions, forming points 4. Surrounding the points is a circle, 5, of angular depressions. Surrounding the circle are triangular figures 6. Between the triangular figures are clusters 7 of depressions, forming the base of pointed figures 8, having diamond-shaped depressions 8^a within them. From between the pointed fig-

ures extend banner-shaped figures 9. Between the banner-shaped figures are ovate depressions 10. Extending from the base to the top of the banner-shaped figures are series of large rosettes 11, and in the spaces between the rosettes are small rosettes 12.

Having thus described my design, the following is what I claim as new therein and desire to secure by Letters Patent:

The design for the ornamentation of glass and other ware herein described and shown, the same consisting of a star, the banner-shaped figures extending from between the points of the star, and ovate depressions between the banner-shaped figures.

THOMAS G. HAWKES.
